UNITED STATES PATENT OFFICE.

CHARLES C. MENGEL, OF LOUISVILLE, KENTUCKY, ASSIGNOR TO MENGEL BOX COMPANY,
OF LOUISVILLE, KENTUCKY, A CORPORATION OF NEW JERSEY.

KNOCKDOWN BOX.

No. 927,264.

Specification of Letters Patent.

Patented July 6, 1909.

Application filed August 31, 1908. Serial No. 450,994.

To all whom it may concern:

Be it known that I, CHARLES C. MENGEL, a citizen of the United States, residing at Louisville, in the county of Jefferson and 5 State of Kentucky, have invented certain new and useful Improvements in Knock-down Boxes, of which the following is a specification.

My present invention pertains to improvements in knock-down boxes, the construction and advantages of which will be herein-after set forth, reference being had to the annexed drawings, wherein:

Figure 1 is a perspective view of the box in 15 its collapsed condition; Fig. 2 a sectional perspective view of the same when assembled; and Fig. 3 a sectional view of a slightly modified structure.

The main object of the invention is to produce a simple, light and yet efficient knock-down box for the transportation, primarily, of material in bulk.

Referring first to Figs. 1 and 2, the sides (which term includes the top and bottom of 25 the box) 1, 2, 3 and 4, have their proximate edges beveled, as at 5, and the intermediate members, 2 and 3, are connected to each other and to the sides 1 and 4 respectively, by wire hinges 6. Said hinges are formed of 30 two interlocked loops, the ends of which are passed inwardly through the sides and, after being carried along against the inner face of the sides, are driven into the same, whereby the hinges are securely held in place. Upon 35 the inner face of each side and at each end thereof is secured a cleat 7, said cleat having at each end a beveled face 8, the angle of which is coincident with the angle of the adjacent beveled edge 5. At one end the cleat 40 is cut away to one side of the beveled face, thereby forming a squared recess 9, while at the opposite end of the cleat is formed a square tongue 10, complementary in size to the recess 9. The heads 11 and 12, and also the 45 sides, are preferably formed of compound lumber, said heads being of such size as to accurately fit the openings formed by the sides when the same are brought to their closed or folded position, as shown in Fig. 2. The 50 proximate edges of the sides 1 and 4 may be secured in place by wires 13 passed through holes 14 formed in said sides, or through eyelets 15 mounted therein.

Under the construction as above set forth, the material within the box is depended upon 55 to hold the heads in place against the cleats. The formation of the cleats renders the box stiff and stable.

Where it is desired to hold the heads in 60 position without depending upon the material within the box, extra cleats, as 16, Fig. 3, may be secured to the sides, said cleats being spaced away from the cleats 7 a sufficient distance to permit the heads to pass 65 between the same.

No claim is made herein, *per se*, to the sides connected by the wire hinges, as that forms the subject-matter of a separate application filed by me of even date herewith.

Having thus described my invention, what 70 I claim is:

1. In a knock-down box, the combination of a series of sides, the abutting edges of which are beveled; wire hinges securing the same together; heads; a cleat mounted upon 75 the inner face of each side and at each end thereof, said cleat having a beveled face at each end which stands in alinement with the adjacent beveled edge of the side; a tongue formed upon one end of the cleat to one side 80 of the beveled face and adapted to fit into a complementary recess formed in the end of the next adjacent cleat; a second series of cleats secured to the inner faces of the sides at each end thereof, said series being spaced away 85 from the first cleats to form a recess for the reception of the heads; and means for securing the parts in their closed position.

2. In a knock-down box, the combination of a series of sides the abutting edges of 90 which are beveled; wire hinges formed of interlooped members connecting the same; a cleat secured to the inner face of each side and adjacent to each end thereof; heads of a size to fit within the sides when the same 95 are brought to their closed position; and means for securing the parts in their closed position.

3. In a knock-down box, the combination of a series of sides the abutting edges of 100 which are beveled; wire hinges connecting the same; a cleat secured to the inner face of each side and at each end thereof, each of said cleats being formed at each end with a beveled face which stands in alinement with 105 the adjacent beveled face of the side, said

cleats being likewise provided at one end with a squared recess and at its opposite end with a squared tongue; heads adapted to fit within the sides when the same are folded; 5 and means for securing the parts in their closed position.

In testimony whereof I have signed my

name to this specification in the presence of two subscribing witnesses.

CHARLES C. MENGEL.
